LIGHTING APPARATUS

Lindsley Schepmoes, New Haven, Conn., assignor
to The Safety Car Heating and Lighting Com-
pany, Inc., a corporation of Delaware

Application September 20, 1944, Serial No. 554,870

12 Claims. (Cl. 240—7.1)

1

This invention relates to lighting apparatus and more particularly to lighting apparatus for use in railroad cars or the like.

One of the objects of this invention is to provide lighting apparatus for railroad cars or the like which will be simple, practical, and thoroughly durable. Another object is to provide apparatus of the above character in which all portions of the car are furnished with an adequate supply of light. Another object is to provide apparatus of the above character which is light and inexpensive in construction, pleasing in appearance, and particularly well adapted for use in railroad cars and the like. Another object is to provide individual lighting under the control of each passenger. Another object is to provide apparatus of the above character which may be readily disassembled to replace worn parts. Another object is to provide new and improved lighting apparatus for a railroad car or the like. Other objects will be in part obvious and in part pointed out hereinafter.

The invention accordingly consists, in the features of construction, combinations of elements, and arrangements of parts, as will be exemplified in the structure to be hereinafter described, and the scope of the application of which will be indicated in the following claims.

In the accompanying drawings in which is shown one of the various possible embodiments of this invention,

Figure 1 is a fragmentary transverse elevation of a railroad car in which the lighting apparatus is installed;

Figure 2 is a side elevation of a pair of seats in a railroad car having the lighting apparatus installed thereon;

Figure 3 is a top plan view of the seats shown in Figure 2;

Figure 4 is a vertical sectional view of one of the fixtures of the lighting apparatus, certain parts thereof being broken away;

Figure 5 is a vertical section taken on the line 5—5 of Figure 4;

Figure 6 is a vertical section taken on the line 6—6 of Figure 4;

Figure 7 is a vertical section of another fixture of the lighting apparatus, certain parts thereof being broken away; and,

Figure 8 is a vertical section taken on the line 8—8 of Figure 7.

As conducive to a clearer understanding of certain features of this invention, it might here be pointed out that many of the lighting systems now in use in railroad cars are inefficient in that

2

certain parts of the car where lights are not needed are overlighted and other parts where light is needed are underlighted. A majority of the present lighting systems are installed in the clerestory of a railroad car, and accordingly because of the distance between the clerestory and the seats, the passengers do not receive adequate illumination for reading. If sufficient illumination is supplied for reading, then the lighting systems give off considerable glare which is disagreeable to and may strain the eyes of the passengers who are not reading. Furthermore, the light in the average railroad car lighting system is not concentrated upon the seats where it benefits the passengers to the greatest degree. Thus, it is another object of this invention to provide apparatus for lighting a railroad car or the like which will overcome the above-named difficulties as well as many others.

20 Referring to Figures 1, 2, and 3, in general the lighting apparatus 10 includes a frame having portions 10a and 10b mounted on the car seats, generally indicated at 11a and 11b. Frame portions 10a and 10b support three lighting fixtures, generally indicated at 12, 13, and 14. Lighting fixtures 12 and 14 are constructed to furnish light to the individual seats positioned under them, and the light from lighting fixture 13 is directed upwardly to illuminate the upper portions of the car.

25 The frame portions 10a and 10b are tubular and may be made either of plastic or metal. At their lower ends these portions are connected to and form a part of the framework of the arms 16 and 17 of seats 11a and 11b. Frame portions 10a and 10b extend upwardly from arms 16 and 17 (Figures 1 and 2) in alignment with the backs of seats 11a and 11b, thence curve forwardly over arms 16 and 17 (Figure 3) and thence curve inwardly so that their upper ends 10c and 10d are facing each other and are positioned over the outer portions of the cushions of seats 11a and 11b (Figure 1). Lighting fixtures 12 and 14 are connected to the upper ends 10c and 10d of frame portions 10a and 10b, and the tubular housing of lighting fixture 13 is connected to the inner ends of fixtures 12 and 14. Lighting fixture 12 is positioned above seat 11a and its operation is controlled by the occupant of that seat through switch 18 (Figure 3), and lighting fixture 14 is positioned above seat 11b and its operation is controlled by the occupant of that seat through switch 19.

30 Lighting fixtures 12 and 14 are similar in construction, and accordingly detailed description of

these fixtures will be limited to fixture 14. Lighting fixture 14 (Figure 4) has a framework including a pair of fittings, generally indicated at 20 and 21, which are connected by longitudinal supports 24 and 25 (Figures 4 and 6). Fittings 20 and 21 are similar in construction and include ring-shaped portions 20a and 21a which are externally threaded and which coat with internal threads formed in the ends of frame portion 10b and the tubular housing of lighting fixture 13, thus to mount lighting fixture 14. Fittings 20 and 21 also include a pair of U-shaped portions 20b and 21b (Figures 4 and 5) which are integrally connected to ring-shaped portions 20a and 21a and which form the supports for the sockets 22 and 23 of the fixture and also for longitudinal supports 24 and 25. Supports 24 and 25 extend lengthwise throughout the fixture and are connected at their ends to the sides of the U-shaped portions 20b and 21b of fittings 20 and 21 by screws 26 (Figure 5).

Sockets 22 and 23 each have metal tongue portions 22a and 23a which extend over the bottom of the U-shaped portions 20b and 21b of fittings 20 and 21 and are connected to these portions by screws 27 and 28. An elongated tubular illuminator, generally indicated at 29 (Figure 4) is mounted on sockets 22 and 23 by means of its prongs 30 and 31 on its opposite ends. Prongs 30 and 31 form electrical contacts with contact elements in sockets 22 and 23 which are connected into the wiring circuit of the lighting apparatus.

A lens, generally indicated at 32, is mounted beneath illuminator 29 (Figures 4 and 6) and extends between fittings 20 and 21. The lens is supported by a pair of flanges 24a and 25a extending inwardly from the lower edges of supporting members 24 and 25. Lens 32 (Figure 6) has a pair of flange portions 32a and 32b extending upwardly from its longitudinal edges. These flange portions have a series of notches 33 (Figure 4) cut therein, pairs of which are aligned transversely across the lens and which are adapted to receive and hold a series of opaque louvres 34 in vertical positions in the fixture. These louvres insure even distribution of the light from the fixture.

The fixture is covered by a tubular shaped housing 35 which is mounted on the cylindrically shaped portions of fittings 20 and 21 and which has a slot 36 extending longitudinally thereof through which the light from the fixture passes. The inner surface of housing 35 acts as a reflector directing rays of light from illuminator 29 downwardly through lens 32 (Figure 4). Because it is mounted on the cylindrically shaped portions 20a and 21a of fittings 20 and 21, housing 35 may be manually rotated with respect to the framework of the fixture so that slot 36 instead of being positioned in alignment with the lens in the fixture is positioned above illuminator 29. When the housing is thus positioned, the interior of the fixture is readily accessible for repairs such as replacing a burnt out illuminator. Housing 35 maintains its position with respect to the fixture through friction between it and the outer surface of fittings 20 and 21.

Referring now to Figure 7, lighting fixture 13 includes a framework comprising fittings 41 and 42 connected by longitudinal supports, generally indicated at 43 and 44. The framework is mounted within the tubular housing, generally indicated at 40, and longitudinal supports 43 and 44 are connected to fittings 41 and 42 by screws 45 which thread into the sides of the

U-shaped portions 41a and 42a of fittings 41 and 42. A pair of sockets 46 and 47 are connected by their tongue portions 46a and 47a and by screws 48 and 49 to the U-shaped portions of fittings 41 and 42. A tubular illuminator, generally indicated at 50, is mounted by its prongs 51 and 52 on sockets 46 and 47 and these prongs contact electrical contacts in the sockets to complete the circuit to illuminator 50. The electrical contacts in the sockets are connected into the electrical circuit of the lighting apparatus by wiring (not shown), which is contained within the frame portions 10a and 10b of the lighting apparatus and passes longitudinally of all of the fixtures in the space between their housings and the longitudinal supports of the frameworks, such as support 43 (Figure 8.) A reflector, generally indicated at 53, is mounted beneath illuminator 50 and its ends are connected to the U-shaped portions of fittings 41 and 42 by screws 54 and 55.

Housing 40 has a cut-out portion 40a therein above illuminator 50 and a plastic globe 56 is positioned within this cut-out portion over illuminator 50. Globe 56 has a pair of flanges 56a and 56b (Figure 8) along its longitudinal edges which coat with the upper edges of the reflector 53 and flanges 43a and 44a of longitudinal supports 43 and 44 to hold the globe in position on the fixture. Globe 56 may be removed from the fixture by flexing it longitudinally and when it is removed from the fixture, the illuminator 50 and other parts of the fixture are readily accessible for repair.

As described hereinabove, fixture 14 is connected by its fittings to fixture 13 and to the upper end 10d of frame portion 10b. Fixture 12 is mounted in a similar manner, one end being connected to the upper end 10c of portion 10a and its opposite end being connected to fixture 13. The lenses in fixtures 12 and 14 face downwardly toward the cushions in seats 11a and 11b (Figure 1) so that the rays of light therefrom illuminate each seat. The opaque louvres 34 (Figure 4) are of material aid in evenly distributing the light from the illuminators in fixtures 12 and 14. As described hereinabove, the rays of light from fixture 13 (Figure 1) are directed upwardly toward the upper portions of the car. Illuminator 50 is preferably of a type which gives off ultra violet rays and globe 56 is of a type which is transparent to ultra violet rays and opaque to visible light. The baggage rack 60 and the ceiling 61 of the car are coated with fluorescent paint, and thus the ultra violet rays from fixture 13 coat with the baggage rack 60 and the ceiling 61 to evenly illuminate the interior of the car. The fixtures 13 on each pair of seats are preferably controlled by a master switch so that the illumination of the car is under the control of the train crew.

Thus lighting apparatus has been disclosed which provides individual illumination for each of the seats in a railroad car. This apparatus is so constructed that it forms a part of the framework of the chair and does not interfere with the operation of the type of seat in which the back is adjustable as indicated by the dotted line 70 (Figure 2). The operation of each seat light is controlled by the occupant of each seat by switches such as switches 13 and 13 (Figure 3) which are readily accessible. The body of the car is evenly illuminated by fixture 13 as the ultra violet rays from this fixture illuminate the fluorescent upper portions of the car. Thus, lighting apparatus has been disclosed which is

practical and efficient in operation and in which the several objects hereinabove mentioned, as well as many others, are accomplished.

As many possible embodiments may be made of the above invention, and as many changes might be made in the embodiment above set forth, all matter hereinabove set forth or shown in the accompanying drawings is to be interpreted as illustrative and not in a limiting sense.

I claim:

1. In lighting apparatus, in combination, a pair of frame members extending upwardly from the arms of a pair of railroad car seats in alignment with the backs of said seats, thence extending forwardly and then inwardly toward each other, three lighting fixtures mounted between the upper ends of said frame members, each of said lighting fixtures including a rigid frame construction with end brackets and with parallel longitudinal members which provide a space for an illuminator and also including a reflector positioned either above or below the space for said illuminator with the side opposite said reflector being adapted to transmit light rays, two of said lighting fixtures having the rays of light therefrom directed downwardly upon the seats positioned therebeneath, individual switch means operable by the occupant of a seat for controlling the operation of each of said last-mentioned fixtures, the third fixture having the light rays therefrom directed upwardly to illuminate the upper portions of the car, and switch means operable by a member of the train crew for controlling the operation of said last-mentioned fixture.

2. In a lighting fixture, the combination of, a pair of bracket members each having an annular portion presenting a substantially cylindrical supporting surface and also having an axially extending bracket portion, a pair of parallel longitudinal members, supporting said bracket members with the bracket portions spaced apart and projecting toward each other with the longitudinal members being spaced from each other and attached at their ends to opposite sides of said bracket members whereby said bracket members and said longitudinal members provide an elongated space defined at the ends by said bracket members and defined at two opposite sides by said longitudinal members, an elongated tubular illuminator positioned longitudinally within said space and supported at its ends by said bracket portions, means presenting a concave reflector surface along one side of said illuminator, and channel globe means positioned along the other side of said illuminator and extending along one side of said space from one of said longitudinal members to the other, each of said longitudinal members having rib means which overlies the adjacent edge of said globe means whereby said globe means is held in position.

3. In a lighting fixture, the combination of, a pair of bracket members each providing a socket adapted to receive the end of an elongated tubular illuminator, a pair of parallel longitudinal members attached at their ends respectively to opposite sides of said bracket members and rigidly holding said bracket members in spaced relationship with said sockets facing each other whereby the longitudinal members and the bracket members define an elongated space, each of said elongated members having a flat wall adjacent the bracket members and defining one side of said space and presenting on its

side opposite said flat wall a contour which is substantially a segment of a cylinder whereby the elongated members and the bracket members may be snugly received within a cylindrical casing construction, means presenting a channel-like concave reflector surface along one side of the zone within said space which is to be occupied by the illuminator supported in said sockets, and a channel globe positioned along the side of said space and opposite said reflector surface with respect to said zone with the globe substantially closing the side of the space between the adjacent edges of said longitudinal members.

4. In a lighting fixture, the combination of, a pair of bracket members each having an annular portion presenting a supporting surface and also having an axially extending bracket portion, said bracket members being positioned in fixed spaced relationship with their bracket portions facing each other, a pair of parallel longitudinal members positioned with their ends fixed respectively to the opposite sides of said bracket members and defining an elongated space, each of said longitudinal members having a substantially flat wall adjacent said bracket members with overlying edge portions which extend beyond the flat wall along the edges of the adjacent sides of said space and also having on the side opposite said bracket members a pair of spaced flanges which form with said edge portion a contour which is a sector of a cylinder whereby said longitudinal members and said bracket members are adapted to be received within a cylindrical casing structure, and a globe supported by said edge portions.

5. A lighting fixture as described in claim 4 wherein said globe is a lens which directs the rays of light, and a plurality of opaque louvres positioned in parallel relationship transversely of said space and adjacent said globe.

6. A lighting fixture as described in claim 4 which includes, a reflector positioned within said space and engaging the edges of said globe to hold said globe against said edge portions.

7. A lighting fixture as described in claim 4 which includes, a cylindrical casing rotatively mounted on said longitudinal members and having an opening which may be positioned in alignment with said globe to permit the passage of light.

8. In lighting apparatus of the character described, the combination of, a pair of frame members extending upwardly in spaced relationship and thence substantially horizontally, a plurality of lighting fixtures mounted in end-to-end relationship upon the upper end portions of said frame members with there being two substantially identical end fixtures; each of said end fixtures including, a pair of bracket members positioned at the ends of the fixture and providing means to support a tubular illuminator positioned therebetween, a pair of parallel longitudinal members supported in fixed relationship with respect to each other and with respect to said bracket members to provide an elongated longitudinal space for the above-mentioned tubular illuminator, means presenting a concave reflector surface along one substantially horizontal side of the space for said illuminator between the parallel edges of said longitudinal members, and globe means positioned along the space for said illuminator opposite said reflector surface and bridging the space between said longitudinal members with each of said longitudinal members

70 having rib means engaging the adjacent edge of

said globe means whereby said globe means is held in position.

9. In lighting apparatus of the character described; the combination of; a pair of frame members extending upwardly in spaced relationship and thence substantially horizontally; a plurality of lighting fixtures mounted in end-to-end relationship upon the upper end portions of said frame members; each of said fixtures including; a pair of bracket members positioned at the ends of the fixture and providing means to support a tubular illuminator positioned therebetween; a pair of parallel longitudinal members supported in fixed relationship with respect to each other and with respect to said bracket members to provide an elongated longitudinal space for the above mentioned tubular illuminator with top and bottom open sides, means presenting a concave reflector surface along one of said open sides between said longitudinal members, and globe means positioned along the other of said sides bridging the space between said longitudinal members with each of said longitudinal members having rib means engaging the adjacent edge of said globe means whereby said globe means is held in position.

10. Lighting apparatus as described in claim 9 wherein at least one of said fixtures has its globe means along the top so as to direct light rays upwardly.

11. Lighting apparatus as described in claim 10 wherein said frame members are mounted on the opposite sides of a pair of railroad car seats in alignment with the backs of said seats and ex-

tend upwardly and thence forwardly so that said lighting fixtures are mounted over the seats, and wherein there are three lighting fixtures the end ones of which direct light rays downwardly to the reading zones in the respective seats.

12. Lighting apparatus as described in claim 11 which includes; a pair of cylindrical casings rotatably mounted respectively around said end fixtures, each of said casings having an opening which may be positioned in alignment with said globe means and also having an inner portion which forms said means presenting a concave reflector surface.
